CONTAINER FOR SHIPPING CAPACITORS

Victor Insetta, Old Westbury, N.Y., assignor to American Technical Ceramics, Division of Phase Industries Inc.

Filed Nov. 29, 1972, Ser. No. 310,260

Term of patent 14 years

Int. Cl. D9—03

U.S. Cl. D9—184

FIG. 1

FIG. 2

FIG. 3

FIG. 4

FIG. 5

FIG. 1 is a perspective view of a container for shipping capacitors showing my new design;

FIG. 2 is a top plan view thereof;

FIG. 3 is a right side elevational view thereof;

FIG. 4 is a front elevational view thereof; and

FIG. 5 is a bottom plan view thereof.

The side opposite that seen in FIG. 3 is a mirror image of the side shown and the back is substantially the same in appearance as the front.

I claim:

The ornamental design for a container for shipping capacitors, substantially as shown and described.
